UNITED STATES PATENT OFFICE

97,656

DESIGN FOR A TEXTILE FABRIC

Arthur White, Uxbridge, Mass., assignor to Uxbridge Worsted Company, Inc., Uxbridge, Mass., a corporation of Massachusetts

Application July 16, 1935, Serial No. 57,661

Term of patent 3½ years

To all whom it may concern:

Be it known that I, Arthur White, a citizen of the United States, residing at Uxbridge, in the county of Worcester, State of Massachusetts, have invented a new, original, and ornamental Design for Textile Fabrics, of which the following is a specification, reference being had to the accompanying drawing, forming part thereof.

In the accompanying drawing:—

Figure 1 is a face view of a textile fabric, showing my new design; and

Figure 2 is a cross-section of said fabric, taken on the line 2—2 in Figure 1.

The design, as shown in the accompanying drawing, comprises series of substantially square

diagonally aligned depressed areas meeting at their corners, and elongated overlapping substantially rectangular raised areas between the series of depressed areas and asymmetrically spacing them on different dimensions of the fabric. The faces of the relatively depressed areas presenting relatively small parallel ribs and the faces of the relatively raised areas presenting relatively coarse parallel interrupted ribs. The fabric is woven and is in a single color.

I claim:—

The ornamental design for a textile fabric, as shown and described.

ARTHUR WHITE.
